UNITED STATES PATENT OFFICE.

JOHN KRAFT, OF JEMEPPÉ-SUR-MEUSE, NEAR LIEGE, BELGIUM.

STARTING AND MANEUVERING APPARATUS FOR TURBINE-STEAMERS.

No. 824,727.

Specification of Letters Patent.

Patented July 3, 1906.

Application filed January 30, 1906. Serial No. 298,680.

To all whom it may concern:

Be it known that I, JOHN KRAFT, engineer, a subject of the Emperor of Austria-Hungary, residing at Jemeppe-sur-Meuse, near 5 Liege, in the Kingdom of Belgium, have invented new and useful Improvements in Starting and Maneuvering Apparatus for Turbine-Steamers, of which the following is a specification.

- 10 A turbine-steamer must have separate turbines for going ahead and astern. Generally speaking, these vessels are provided with three sets of turbines, each driving a screw. The central or high-pressure turbine is only 15 used for forward running, and the steam is led into it directly from the boilers. From this central turbine the steam is led into the two low-pressure turbines, from whence it escapes to the condensers. During maneuvers only 20 the two lateral turbines are used, the steam being led into them directly from the boilers and given ingress both to the forward-motion and backward-motion parts of these turbines.
- 25 This invention relates to a maneuvering apparatus which shall allow at will the turbines to be run at any speed in the direction which may be required and give full control of the different valves; and it consists, essentially, in the special arrangements and combinations of parts, as will be hereinafter fully described, and pointed out in the appended claims.

The system described hereinafter supposes 35 the use of three turbines; but the same plan may be followed in dealing with a combination of any number of turbines.

Referring to the annexed drawings, Figure 1 is a vertical section of an apparatus constructed according to the invention. Fig. 2 40 is a transverse section taken on line 1 1 of Fig. 1. Fig. 3 is a view similar to Fig. 1, illustrating a modification. Fig. 4 is a transverse section taken on line 3 3 of Fig. 4.

45 In the said drawings, A is the steam-pipe, leading from the boilers. The regulator-valve B is usually left open and is only closed (by a governor) in case of the turbine "racing" beyond its proper maximum speed.

50 The steam penetrates into the space C C C, which contains two stop-valves D and E. In the drawings these valves are shown as of the double-seated balanced type; but other forms may be used. The first valve D is used 55 for running ahead. It admits the steam to

the space F, whence it passes through a strainer G into the pipe G', leading to the central turbine. The second valve E is used for maneuvers, which consist in running the lateral turbines independently at will backward or forward, or stopping them. It gives entrance to the steam into the space H, where it branches off into the two spaces I I on each side; but before reaching these spaces it must pass through the two valves J J. These 60 valves are only opened during maneuvers and may be kept closed under normal conditions of running. They constitute in reality a mere safety device in case one or the other of the lateral turbines should be out of order 65 and it should become necessary to isolate it. Strictly speaking, these valves J J can be dispensed with, as a turbine can be isolated by means of the distributing-piston, which I shall describe farther on.

75 The characteristics, particularly of the new system and that which differentiates it from all similar ones hitherto proposed, lies in the method of working the valves D and E. When the vessel is not running, these two 80 valves D and E are closed and kept on their seats by means of the adjustable springs K and L. In this position they are independent of their working gear, which shall now be described. The stop-valves are controlled 85 by a hand-wheel M, of which the spindle N forms a screw, working in the nut O, lodged in the lever P, pivoted on a trunnion p, suitably mounted in a bracket p'. For ordinary ahead traveling, the stop-valve D must be 90 opened by turning the hand-wheel; but the valve only begins to open when the dead space Q has been traversed. During the interval in which this takes place the second stop-valve E is kept closed by the spring L. 95 For maneuvers it is necessary to open the stop-valve E, which is done by turning the hand-wheel in the contrary direction to that necessary for opening D. Here, again, the valve E only begins to open after traveling 100 through the dead space R, D being kept closed by the spring K. Thus the two stop-valves are controlled by a single hand-wheel which gives great simplicity to the mechanism.

105 In the above combination the lever P opens the valves, and the springs K and L close them; but this arrangement may be reversed, so as to make the hand-wheel close the valves and the springs open them. In 110

this case the valve-spindles may be made of large diameter, so as to make the steam-pressure assist the action of the springs.

It has been mentioned above that during 5 maneuvers the steam is allowed into the spaces I I. Each of these spaces contains a hollow balanced distributing-piston S, worked by a lever put in motion by a starting-engine. (Not represented on the drawings.) The 10 distributing-piston S is shown in its mean position, in which all the openings of the lantern-valves T giving access to the annular 15 passages U and V are closed. In its lower position the piston uncovers the openings of the upper lantern-valve, thus allowing the steam to penetrate into the annular passage U and from thence by the pipe W to the corresponding lateral turbine, which it causes to run forward. In its upper position the 20 distributing-piston uncovers the openings of the lower lantern-valve, and the steam passing into the annular passage V and through the pipe X reaches the corresponding lateral 25 turbine, which it drives backward.

25 In the arrangement shown by the drawings the steam is let in above the distributing-piston S, over the upper edge of which it passes on its way to the turbine; but the contrary arrangement may be adopted and the 30 steam led into the space between the two pistons and allowed to pass to the turbines by the inner edges of these pistons. If preferred, flat slide-valves may be used instead of the distributing-pistons, making at the 35 same time the starting-engines more powerful on account of the greater resistance to be overcome.

In the modification shown in Fig. 3 the main stop-valves D and E, with their working 40 gear M P, are disposed exactly as in the first arrangement, but the steam distribution while performing maneuvers is entirely different. The distributing-pistons and the starting-engines for working the steam distribution 45 are suppressed, as also are the two precautionary valves J J. Instead of these, two valves *a* and *b* are fitted on each side, giving access to the corresponding lateral turbine, one for forward and the other for backward 50 running. The working gear of these valves is similar to that of the main stop-valves, but of smaller dimensions, and its method of operation is the same as that described above for the larger valves. The main valves are 55 controlled, as before, by the large hand-wheel M and the maneuvering-valves by the small hand-wheels *d d*, mounted on spindles *e*, each working in a nut *f*, lodged in a lever *g*, acting, as already described with reference to 60 lever *P*, on the rods of the valves *a b*, which are kept closed by springs *h l*.

Having thus described my invention, what I claim is—

1. A starting and maneuvering apparatus for turbine-steamers comprising a main stop-valve, for forward running, a special maneuvering-valve giving the steam access to the lateral turbines only and a single lever and hand-wheel controlling both valves, the opening of one or the other of these two valves 70 taking place according to the direction in which the hand-wheel is turned substantially as described and for the purpose set forth.

2. A starting and maneuvering apparatus for turbine-steamers comprising a main stop-valve, for forward running, a special maneuvering-valve giving the steam access to the lateral turbines only, a single lever and hand-wheel controlling both valves, the opening of one or the other of these two valves 75 taking place according to the direction in which the hand-wheel is turned and suitably worked, distributing-pistons for delivering the steam to the lateral turbines so as to allow these to drive the vessel ahead or astern at will substantially as described and for the purpose 80 set forth.

3. A starting and maneuvering apparatus for turbine-steamers comprising a main stop-valve for forward running, a special maneuvering-valve giving the steam access to the lateral turbines only, a hand-wheel, a screw-threaded spindle rotated by said hand-wheel, a nut in which the said spindle works, a lever supporting the said nut, a trunnion on 90 which the said lever is adapted to be rocked and valve-rods acted upon by the ends of the said lever, the opening of one or the other of the two valves taking places according to the direction in which the hand-wheel is turned, substantially as described and for the purpose 95 set forth.

4. A starting and maneuvering apparatus for turbine-steamers comprising a main stop-valve for forward running, a special maneuvering-valve giving the steam access to the lateral turbines only, a single lever and hand-wheel controlling both valves, the opening of one or the other of these two valves taking 100 place according to the direction in which the hand-wheel is turned, two stop-valves for each of the lateral turbines and a single lever and hand-wheel device controlling the said stop-valves substantially as described and for the purpose 105 set forth.

In testimony whereof I have signed my name to this specification in the presence of two subscribing witnesses.

JOHN KRAFT.
